tion of New York

Application April 7, 1944, Serial No. 529,981

12 Claims. (Cl. 250—1.66)

1

The present invention relates to manual and automatic tuning of resonant circuits, and more particularly, to manual and automatic frequency control of tunable oscillators.

An object of the present invention is to provide improved methods and apparatus for tuning control of resonant circuits.

Another object of the present invention is to provide improved methods and apparatus for controlling the frequency of a superheterodyne high frequency oscillator.

A further object is to provide improved high-gain amplifying means for signals derived from a frequency discriminator.

Another object is to provide an improved method and apparatus for sweeping the frequency of an oscillator through a tuning range in a predetermined manner, permitting transfer to automatic frequency control upon detection of a satisfactory oscillator frequency.

A further object is to provide an improved stable amplifier for the direct current component of a periodically varying signal.

Further objects will become apparent from the following description taken in conjunction with the drawings, of which:

Fig. 1 is a block diagram showing an embodiment of the present invention incorporated for illustrative purposes in a radio object detection system;

Fig. 2 is a schematic wiring diagram showing circuit details of certain parts of Fig. 1; and

Fig. 3 is a graphic representation of the operation of frequency sweep control apparatus included in the system of Fig. 2.

Similar characters of reference are used in Figs. 1 and 2 to indicate corresponding parts.

The invention will be described in an embodiment especially adapted for use with object detecting or locating devices, such as those including electromagnetic pulse transmitters and cooperating superheterodyne receivers. However, it is to be understood that the invention is not restricted to use in such systems.

Fig. 1 shows a general block diagram of one form of system including the present invention. In this figure, a pulse generator 21 of any conventional type produces a periodic pulse wave preferably having pulses of relatively short duration, such as of the order of one-half to two microseconds, and with a pulse repetition frequency in the audio range, such as in the neighborhood of two thousand pulses per second. The output of generator 21 serves to control a pulsed high-frequency transmitter 22 feeding a trans-

2

mitting antenna 23. Transmitter 22 may be of any suitable type adapted to produce an output carrier frequency preferably in the ultra high frequency range with a modulation envelope corresponding to the output of pulse generator 21. In this way, energy radiated from antenna 23 will be a series of short pulses of ultra high frequency energy with a pulse repetition frequency determined by generator 21.

10 The pulse waves radiated by antenna 23 will be reflected by any objects in its path, and a portion of the reflected energy will excite a receiving antenna 24 feeding a suitable mixer 25 to which is also supplied a heterodyning or beating frequency wave from a local oscillator 26 as in standard superheterodyne receiver circuits. The output of mixer 25 then will have a frequency corresponding to the difference between the transmitted carrier frequency and that of oscillator 26, this difference frequency being known generally as an intermediate frequency. The intermediate frequency wave output from mixer 25 may be suitably amplified in an intermediate frequency amplifier 27 and then be used to excite 15 any suitable type of signal utilization circuit 28. The details of circuit 28 form no part of the present invention, but it may be generally noted that the intermediate frequency wave supplied to circuit 28 may be utilized to indicate the position 20 and/or movement of the remote reflecting object.

Since the received wave is generally of relatively low amplitude, requiring high amplification in the intermediate frequency amplifier 27, it will be appreciated that amplifier 27 will generally be 25 of a highly selective, high-gain character usually referred to as a narrow pass-band amplifier. In order to prevent the intermediate frequency output of mixer 25 from deviating from the pass-band of amplifier 27, which would cause markedly lowered gain and sensitivity, it is necessary 30 to maintain local oscillator 26 at a substantially fixed frequency difference with respect to the transmitter carrier frequency.

According to the present invention, an improved 35 form of automatic frequency control or frequency stabilized system is provided for controlling the local oscillator 26. For this purpose, in broad terms, an intermediate frequency signal produced by heterodyning the outputs of transmitter 22 and oscillator 26 is applied to a frequency responsive circuit which controls the frequency of oscillator 26 to maintain the intermediate or difference frequency substantially 40 constant. According to former practice, the difference frequency signal for automatic frequency 45

control would be derived from the receiver mixer 25 or receiver intermediate frequency amplifier 27. However, this arrangement is subject to the distinct disadvantage that in the ultra high frequency range, where crystal mixers are used with frequencies of the order of magnitude of 10^{10} cycles per second, such crystal mixers become easily saturated by very high amplitude pulses or signals which may be received by the mixer.

In the arrangement shown, these harmful effects of crystal saturation are avoided by use of a separate mixer 29 for the frequency control system, independent from the signal mixer 25 used in the actual object-detecting circuit itself. As shown in Fig. 1, local oscillator 26 also supplies energy to automatic frequency control mixer 29, whose other input signal is supplied from the output of transmitter 22 through a suitable attenuator 31 of any desired type which will attenuate the transmitter output to a value incapable of producing saturation in the frequency control mixer crystal. The intermediate or difference frequency derived from mixer 29 is suitably amplified in an intermediate frequency amplifier 32 and used to actuate an automatic frequency control circuit 33 which readjusts the output frequency of oscillator 26 to the desired value. Amplifier 32 is also controlled from the pulse generator 21 through a gate control circuit 34 for purposes later to be described.

The actual circuit arrangements of gate control 34, I. F. amplifier 32, A. F. C. circuit 33, and local oscillator 26 are shown in more detail in Fig. 2. In this figure, tube 35 is the last stage of amplifier 32, which may include entirely conventional preceding stages, if desired. As shown, tube 35 is of the pentode type and has a conventional circuit for amplifiers of its type, with the exception that the suppressor grid 36, instead of being connected directly to the cathode, is connected to be controlled by the gate control circuit 34, later to be described. For the present, it may be assumed that the potential supplied to suppressor grid 36 by control circuit 34 is substantially the potential of the cathode of tube 35, permitting amplification of the intermediate frequency wave by the tube 35.

The output circuit of tube 35 includes a transformer 37 having a primary 38 tuned to the desired difference between transmitter and local oscillator frequencies and a center-tapped secondary 39. A coupling condenser 41 connects the intermediate-frequency high-potential terminal of primary 38 to the center tap 42 of the secondary 39. The other terminal of primary 38 may be connected through filter resistor 44 to the positive high-potential terminal 43 of a direct-current source whose opposite, or negative terminal, is grounded. An intermediate-frequency by-pass condenser 45 provides a ground return for the intermediate frequency component of anode current of tube 35.

Secondary 39 may also be tuned to the desired intermediate frequency by an adjustable condenser 46. The tuned circuit 39, 46 may be provided with a broad band characteristic by a shunt resistor 47. An intermediate frequency choke coil 48 is also connected to center tap 42. A pair of rectifier tubes 49 and 51 have their anodes connected to respective outer terminals of secondary 39, their cathodes being connected to the other terminal of choke 48 through respective load resistors 52 and 53 shunted by respective intermediate-frequency by-pass condensers 54 and 55. The cathode of tube 51 is grounded at 56.

Rectifiers 49 and 51 with their associated circuit elements form a conventional type of frequency discriminator and provide, between terminal 57 (connected to the cathode of tube 49) and ground, an output reversible polarity voltage corresponding in polarity and magnitude to the sense and amount of deviation of a prevailing or actual input intermediate frequency from a desired value corresponding to the resonant frequency of transformer 37.

Because of the pulsed character of the wave received by mixer 29 from transmitter 22 through attenuator 31, the output potential derived between terminals 57 and 56 will be correspondingly pulsed and will therefore actually be a series of reversible-polarity potential pulses, the magnitude of the pulses corresponding to the amount of frequency deviation and the polarity of the pulses corresponding to the sense of frequency deviation of the local oscillator frequency from its desired value.

The alternating components of this pulsed frequency-responsive potential wave are amplified in a conventional resistance-capacity coupled alternating-current amplifier 58. The output of amplifier 58 is coupled to the input of a conventional phase inverter 59 which produces at the terminals 60, 60', equal magnitude, opposite polarity potential pulses. These pulses are applied to the grids of balanced pulse detector tubes 61 and 62 forming part of the present invention, through condensers 61 and 71.

The anodes and cathodes of tubes 61 and 62 are connected in a series circuit, comprising positive potential terminal 63 of a source of positive potential with respect to ground, the anode-cathode circuit of tube 61, an adjustable voltage divider resistor 65, the anode-cathode circuit of tube 62, and a negative potential source 66. A potential varying substantially as the potential of terminal 60 is applied to the control grid of tube 61 through high-frequency coupling and direct-current blocking condenser 67 and a grid-leak resistor 68, the cathode of tube 61 being connected to ground in an alternating-current sense by a by-pass condenser 69. Similarly, a potential varying substantially as the potential of the terminal 60' is connected through a high-frequency coupling and direct current blocking condenser 71 to the control grid of tube 62, a similar grid-leak resistor 72 being provided and the cathode of tube 62 being by-passed to ground for alternating current by the condenser 73. The anode of tube 62 is also grounded for alternating current by condenser 74.

When the intermediate frequency output of amplifier 32 is at the desired frequency during the occurrence of the transmitted pulses, equal rectified currents flow through the frequency discriminator tubes 49 and 51. Accordingly, equal and opposite potentials are produced across condensers 54 and 55, with the result that terminal 57 is at ground potential. In this situation, no signal voltage is applied to the grid of amplifier tube 58, and the succeeding stages remain quiescent.

If, on the other hand, the signal delivered through I. F. amplifier 32 deviates from the desired frequency, unbalanced intermediate frequency voltages are applied to discriminator diodes 49 and 51 during the transmitted pulses, and a pulsating potential wave characterized by alternating components at the frequency corresponding to the pulse repetition rate and to harmonics thereof, is produced at terminal 57 with

respect to ground. For frequency deviations in one direction, the potential of terminal 57 with respect to ground is positive during the detection of transmitted pulses, while for a frequency departure in the opposite sense, terminal 57 is negative with respect to ground during the brief transmitted pulses. Thus, the potential at terminal 57 may have a positive value during a short time interval such, for example, as one microsecond (during the ultra-high frequency transmission of transmitter 22, as determined by pulse generator 21), thereafter remaining at substantially ground potential during a succeeding time interval such as approximately one millisecond (the interval between successive pulses) after which the cycle is repeated. Amplifier 58, adapted to amplify only the alternating current components of the signal potential produced at terminal 57, accordingly applies to the grid of phase inverter 59 a signal which is strongly negative with respect to a normal (average) grid potential value during an interval of the order of one microsecond, after which the grid of tube 59 remains at a potential very slightly more positive than the normal quiescent grid potential during the interval between successive pulses.

Phase inverter 59, when provided as above described with pulsating potential signals, produces at terminals 60 and 60' rapid potential excursions of opposite polarities. Thus, during transmission of a pulse initiated by pulse generator 21, terminals 60 and 60' are at greatly different potentials, one being greatly positive and the other equally negative with respect to the normal quiescent potentials at these points. During the intervals between the transmission pulses initiated by pulse generator 21, the potentials of terminals 60 and 60' are only minutely different from their quiescent potential values, and with opposite directions of departure from those obtained during the transmission of the aforesaid pulses.

Due to the changes of potential of terminals 60 and 60', the grid-cathode circuits of detector tubes 61 and 62, including condensers 67, 69 and 71, 73, respectively, provide the diode detection which is characteristic of the input circuit of a grid-leak detector to which alternating current signals are applied. Thus, if the frequency departure of the signal introduced by amplifier 32 to transformer 31 is of such a sense as would produce a positive potential pulse at the grid of tube 61 during the transmission from pulsed transmitter 22, the grid-leak detector 61 will operate to produce an average grid potential negative with respect to the cathode, exceeding the average difference of potential of the grid of tube 62 with respect to the cathode of tube 62. Accordingly, the average cathode-anode resistance of tube 62 is lower than the cathode-anode resistance of tube 61, and the direct-current potential at any point along potentiometer 65 is accordingly shifted in a negative direction with respect to the quiescent potential at that point. Conversely, if the output frequency of amplifier 32 is shifted in an opposite direction from the normal or desired frequency, the grids of tubes 61 and 62 will make opposite excursions during the operation of transmitter 22 under control of pulse generator 21, and the direct-current potential at any point along potentiometer 65 will be shifted in a positive direction from its quiescent value. In this way, frequency shifts are converted into corresponding changes in potential at a point, such as at arm 75, of divider 65.

Capacitors 69, 73 and 74 are sufficiently large to

prevent reproduction at any point along potentiometer 65 of the pulsed wave characteristic of the signals applied to the grids of tubes 61 and 62. For any output frequency of intermediate frequency amplifier 32, potentiometer slider arm 75 may be adjusted to provide positive, negative, or zero potential with respect to the ground. The potential difference between discriminator output terminal 57 and ground changes from a positive or a negative value during transmitted pulses resulting in intermediate frequency currents in amplifier 32 different from the desired intermediate frequency, to zero potential difference during the intervals between transmitted pulses. Thus, during a series of transmitted pulses characterized by a given discrepancy between the frequency of the intermediate frequency signal and the desired intermediate frequency, the time variations of the potential of terminal 57 with respect to ground may be analyzed into a direct component plus a series of alternating components.

According to former practice, the alternating components of potential of terminal 57 would be suppressed by a relatively large by-pass capacitor connected between this point and ground, and a direct-coupled amplifier would be used instead of the present alternating-current amplifier and detector system including vacuum tubes 58, 59, 61 and 62. Direct coupled amplifiers suitable for high-gain amplification of a direct potential usually are characterized by unstable performance and great difficulty of adjustment. The alternating-current amplifier and detector system described above overcomes these disadvantages, affording a highly amplified, stable reproduction at potentiometer arm 75 of the direct potential component at terminal 57 by the use of high-gain and stable amplifiers which amplify the alternating components of the signal in preference to the unidirectional component.

Slider arm 75 of potentiometer 65 is connected through resistor 76 to automatic frequency control terminal 77 of single-pole, double-throw switch 78. When the blade 79 of switch 78 is positioned for contact with terminal 77, a version of the potential of potentiometer slider arm 75 is applied through a resistor 80 to the grid of oscillator control tube 61. This tube serves as a variable series resistance in the circuit supplying oscillator tube 82 from positive anode potential source 83. By virtue of the high resistance of resistor 80, the grid potential of tube 61 is confined to a range from very slightly positive values to strongly negative potential with respect to the cathode 84. Thus, the cathode-to-anode resistance of tube 61 may vary from the order of a hundred ohms to an almost infinite resistance, thus permitting wide-range control of the strength of oscillations generated by oscillator 82. The alternating current output of heater oscillator 82 is coupled through transformer 85 to a heater element 86 forming part of a variable separation strut 90 used to control the spacing between flange 87 and flange 88 of velocity modulation tube 26. This oscillator is of the general type shown in Fig. 2 of Patent 2,250,511 to Varian et al., July 29, 1941, but in which the tuning is performed by varying the spacing between grids included in the resonator, as by varying the spacing between the rigid flanges 87, 88 connected to said grids.

Velocity modulation tube 26 forms the local oscillator of a superheterodyne receiver system, as shown in Fig. 1, with output connector 89 available for connection to received signal mixer 25.

A similar output connector (not shown) may be provided in velocity modulation tube 26 for connection to the automatic frequency control mixer 29, from which intermediate frequency amplifier 32 receives its excitation.

An optional manual frequency control arrangement is provided by means of terminal 91 of switch 78, to which is connected the variable arm 92 of potentiometer 93. Potentiometer 93 is grounded at one end, being also connected to cathode 84 of variable resistance heater oscillator control tube 81. Potentiometer 93 is connected at the opposite end to the negative terminal 94 of a source of high potential whose other terminal (not shown) is grounded, so that when blade 79 of switch 78 is positioned in contact with terminal 91, the grid potential of tube 81 may be adjusted by means of manual control 92 completely independently of the operation of the automatic frequency control system.

The variable separation tuning strut 90 of the velocity modulation tube 26, shown as local oscillator for the superheterodyne receiver, operates to vary the volume of the resonant chamber 95 and so to increase the frequency of oscillation of tube 26 when the temperature of the tuning strut is increased by an increase of the heating power applied by oscillator 82 through transformer 85 to the heating element 86. Thus, if switch blade 79 is in position for manual tuning control, movement of potentiometer arm 92 along potentiometer 93 toward the grounded terminal decreases the resistance of series resistance tube 81, permitting the amplitude of oscillation in heater oscillator 82 to increase, and thus to increase the temperature of the variable strut 90, increasing the frequency of oscillator 26.

During automatic frequency control operation of the system, with switch blade 79 positioned in contact with terminal 11, any departure of the frequency of the signals amplified in amplifier 32 from a normal or desired frequency causes a change of the direct potential of slider arm 75, which in turn, varies the potential applied to the grid of series resistance tube 81, and so causes a temperature variation of oscillator 26 in a direction to restore the intermediate frequency signal to the proper value for normal operation.

In the event that when blade 79 of selector switch 78 is positioned for automatic frequency control, the frequency of oscillator 26 is greatly different from the desired frequency, the resulting intermediate frequency signal amplified in I. F. amplifier 32 and applied to primary 38 of transformer 37 may be so far removed from the resonant frequency of transformer 37 as to prevent transfer of the intermediate frequency signal to the discriminator tubes 49 and 51, or may even be outside the pass-band of amplifier 32. In this case, terminal 57 will remain at ground potential in spite of the departure of frequency of oscillator 26 from the desired oscillator frequency, so that the automatic frequency control circuit is unable to vary the voltage applied to heater control tube 81 and thus unable to vary the tuning of oscillator 26 to restore normal operation.

In order to overcome this possibility, a push-button reset circuit is provided including storage capacitor 95', relay 96, push-button switch 97, potential source 98 and resistor 99. If no signal indication appears in signal utilization circuit 28, indicating that the frequency of local oscillator 26 may be far removed from the proper local oscillator frequency, push-button switch 97 may be

depressed to bring arms 101 and 102 of relay 96 into contact with stationary contacts 103 and 104 respectively. This operation charges condenser 95' to substantially the negative potential of source 94', at the same time reducing the potential of the grid of control tube 81 to ground potential, equal to the potential of cathode 84.

In Fig. 3 is shown a graph of the voltage E_g applied to the grid of tube 81 with respect to the cathode, and a simultaneous graph of temperature T_s of the variable tuning strut of ultra high frequency oscillator 26. In this graph of temperature T_s and grid potential E_g against time t , time t_0 is assumed to represent an arbitrary time at which the grid of tube 81 is at a substantially constant finite negative potential E_0 , determined by the position of arm 75 on potentiometer 65, the anode-cathode resistances of tubes 61 and 62 being equal and the temperature of the variable tuning strut is held at a corresponding value T_0 by the power applied by oscillator 82 to heater element 86. At the time t_1 , push-button switch 97 is depressed, closing contacts 101, 103 and 102, 104 of relay 96, and almost immediately changing the grid potential of tube 81 to cathode potential, thus permitting maximum output of oscillator 82, with the resultant substantially exponential temperature rise indicated by portion $a-b$ of curve T_s . Also during the momentary contact of push-button switch 97, condenser 95' is charged to substantially the negative potential of D. C. source terminal 94', as described above.

Upon release of push-button switch 97 at time t_2 the contact of arm 101 and terminal 103 is broken, and arm 102 is returned to its normal position in contact with terminal 105. The latter operation applies the full negative potential of capacitor 95' to the series resistance circuit, including resistor 99 and resistor 106. A fraction 40 of the potential across condenser 95 is applied through resistor 80 to the grid of series resistor tube 81. As shown by the abrupt drop $g-h$ of curve E_g from zero potential to a maximum negative potential at time t_2 , this condenser potential 45 is initially very large, but decreases exponentially as shown at $h-k$ as the condenser 95 discharges through resistors 99 and 106.

As a result of the initial abrupt application of high negative grid potential to heater oscillator 50 control tube 81, the power delivered by oscillator 82 to heater element 86 is abruptly turned off, with the result that the temperature of strut 90 decreases as shown by portion $c-d$ of curve T_s toward a minimum temperature value obtained 55 at time t_3 , thereafter returning to the value T_0 along a protracted exponential curve $d-e$ generally corresponding to the exponential discharge curve $h-k$ of condenser 95.

The frequency of the oscillatory energy produced by tube 26, meanwhile, follows a curve substantially similar to the curve of strut temperature T_s . Thus, the tube 26 is tuned to a maximum oscillation frequency during the period between t_1 and t_2 , while push-button switch 97 is depressed, after which the release of push-button switch 97 permits the frequency of the oscillator to decrease toward a minimum frequency along a curve similar to that shown for T_s between time t_2 and time t_3 .

If the desired operating frequency for oscillator 70 26 is obtained when the tunable strut is heated to the temperature value designated, for example, at R in Fig. 3, then at this point in the downward temperature excursion of the adjustable 75 tuning strut, the intermediate frequency pro-

duced in amplifier 32 will reach the proper value for balanced, normal operation of the frequency discriminator 50 employing tubes 49 and 51. Upon further decrease of temperature of the strut and a similar further decrease of the output frequency of oscillator 26 past the tuned frequency of discriminator 50, the frequency discriminator system causes a sharp change of potential of potentiometer slider 75 in a positive direction as indicated by dotted curve Eg' , shown becoming effective at time T_R . The output circuit of tubes 61 and 62 is so designed in relation to capacitor 95', resistor 99 and resistor 106 as to permit superior control by the changing potential output of tubes 61 and 62 so that the excursion of voltage Eg along curve 108 is abruptly changed as shown in dotted curve Eg' , permitting the frequency of oscillation of tube 26 to remain substantially constant at the desired operating frequency as shown by dotted line T_s' .

If the total tuning range of high frequency oscillator 26, as provided by the strut heating capability of heating oscillator 82 is substantially greater than twice the normal operating frequency of amplifier 32 and the associated frequency discriminator employing tubes 49 and 51, a strut temperature lower than that designated at R in Fig. 3 may be found as by positioning switch blade 79 in contact with manual control terminal 91 and by variation of the position of slider 92 on potentiometer 93 at which the correct intermediate frequency is produced in amplifier 32. Thus, at temperature R the frequency of local oscillator 26 may be higher than the ultra high oscillation frequency of transmitter 22 by a margin equal to the normal frequency of I. F. amplifier 32; while, on the other hand, with the temperature of strut element 86 reduced to R' , the frequency of local oscillator 26 may be lower than the transmitter frequency by the same margin. When the frequency of local oscillator 26 corresponds to temperature R , the amplified discriminator output direct potential provided at arm 75 by tubes 61 and 62 is properly sensed for compensation or suppression of any normal variations of frequency of oscillator 26 relative to the carrier frequency of pulsed transmitter 22. On the other hand, when the frequency of oscillator 26 corresponds to strut temperature R' , the sensing of the direct potential output of tubes 61 and 62 is such as to tend to withhold the temperature of heater element 86 from the temperature designated R' . Accordingly, it is essential for best operation of the system that normal strut temperature R be approached from a predetermined temperature extreme, such as shown in Fig. 3, as maximum temperature, T_{max} .

A feature of the push-button reset circuit incorporated in the frequency control system shown resides in the method of forcing heater oscillator 82 to a predetermined operating condition independent of the potential of potentiometer arm 75, to tune the resonant circuit of oscillator 26 to a predetermined frequency extreme, and of thereafter permitting heater element 86 to vary the output frequency of oscillator 26 along a curve of predetermined strut temperature gradient toward a second extreme of the oscillator tuning range, and further permitting the output of the frequency discriminator, amplifier and detector system, including tubes 49, 51, 58, 59, 61 and 62, to exercise predominant control over the grid potential of control tube 81 when a signal of the proper frequency is provided in I. F. amplifier 32.

From the description of operation of the auto-

matic frequency control system, it will be readily apparent that the direct potential of potentiometer arm 75 is determined by intermediate frequency current pulses rectified differentially through rectifiers 49 and 51, during periods of transmission of transmitter 22 as controlled by pulse generator 21. During the intervals between transmission pulses, I. F. amplifier 32 and the frequency discriminator 50 comprising tubes 49 and 51 should remain quiescent. During these intervals between the controlling pulses from pulse generator 21, which are usually much longer than the control pulse duration, it is possible that radio frequency signals received from external sources may excite I. F. amplifier 32, and so cause an incorrect frequency measurement by the frequency discriminator system. In order to guard against such interference, gate control 34 may be provided as a link between the transmitter pulse generator 21 and intermediate frequency amplifier 32 to render the latter inoperative during the intervals between pulses issuing from generator 21.

Gate control 34 may comprise a pentode tube 121 provided with output coupling resistor 122 connected between the anode 123 of the tube and suppressor grid 36 of amplifier tube 35. A load resistor 124 couples anode 123 to ground, permitting the flow of anode-cathode current through cathode 126 and biasing resistor 127 connected to the negative terminal 128 of a suitable potential source whose other terminal is grounded. A resistor 129 and a capacitor 131 may be connected in parallel between ground terminal 132 and screen grid 140 of tube 121 to provide screen grid voltage of a proper value. The control grid circuit of tube 121 is coupled by means of resistor 133 and capacitors 134 and 135 to output terminals of pulse generator 21, so that a high potential negative pulse may be applied to control grid 136 during the radiation from pulse transmitter 22 of a pulse initiated by pulse generator 21.

When grid 136 is reduced to a high negative potential with respect to cathode 126 by a signal pulse issuing from generator 21, anode current flow through output resistor 124 is terminated, reducing the potential applied to suppressor grid 36 to ground potential, and thus permitting normal amplification by I. F. amplifier 32. During the intervening periods between pulses from generator 21, the control grid 136 remains at a moderate or low negative potential with respect to cathode 126, permitting the flow of current through output resistor 124 to anode 123, and thus biasing suppressor grid 36 to a high negative potential, preventing operation of amplifier 32.

Thus, the gate control 34 may be used to guard the intermediate frequency amplifier 32 against passage of an amplified output signal to frequency discriminator 50, and so to suppress interference from signals received from external sources during the intervals between transmitted pulses.

As described above, an automatic frequency control system is provided in which any discrepancy from a desired value of the frequency of oscillations intermittently supplied by a source, is detected in a frequency responsive system comprising a frequency discriminator adapted to produce pulsating output signals indicative of said discrepancy, an alternating-current amplifier adapted to produce an amplified version of the alternating components of said pulsating output signals, and a detector adapted to produce an output potential representative of the time-aver-

age of pulsating output signals from the discriminator.

The combination of the frequency discriminator, the alternating current amplifier, and the detector thus serves as means for producing an amplified output potential sensitive to the frequency of the signals applied to the discriminator. The output potential of the above apparatus is applied to a frequency control system in such a sense as to suppress discrepancies from a desired frequency of the signals applied to the frequency discriminator.

Gate control 34 insures that the above frequency sensitive means is operative only during the transmitted pulses, thus insuring against interference to the frequency control system from unwanted sources.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. Apparatus for producing electrical oscillations at a frequency of a predetermined difference from the frequency of oscillations of a generator of periodic short-duration pulses of radio-frequency oscillations separated by relatively long time intervals, comprising an adjustable radio-frequency oscillator, a mixer coupled to said oscillator to receive energy therefrom and also adapted to receive energy from said generator during said pulses to produce a heterodyne signal, a frequency discriminator coupled to said mixer for providing output potential pulses of magnitude and polarity dependent on the frequency of said heterodyne signal, amplifying means coupled to said discriminator and adapted to amplify alternating current components of said output potential pulses preferentially to direct current components thereof, balanced detector means coupled to said amplifying means and adapted to produce a substantially direct output potential of intensity dependent on the intensity of said discriminator output potential pulses, and tuning means responsive to said balanced detector direct output potential for adjusting the frequency of said oscillator to suppress frequency variations of said heterodyne signal.

2. Apparatus as claimed in claim 1, further including means responsive to said generator for decoupling said frequency discriminator from said mixer during said time intervals of separation of said radio frequency pulses.

3. Apparatus as claimed in claim 1, further including control means coupled to said tuning means for tuning said oscillator to a predetermined frequency during a brief interval and thereafter varying said oscillator frequency at a predetermined rate and in one direction from said predetermined frequency.

4. Electrical apparatus for producing a substantially constant unidirectional output potential of magnitude dependent on the frequency of periodically interrupted electrical oscillations, comprising frequency-sensitive means responsive to said periodically interrupted oscillations to produce a potential similar in wave form to said interrupted oscillations and dependent in amplitude on the frequency of said oscillations, detector means for deriving the envelope of said last-named potential alternating-current ampli-

fying means coupled to said detector means for producing an amplified version of the alternating current component of the output of said detector means, and balanced detector means coupled to said amplifying means to provide an output potential of magnitude dependent on the frequency of said oscillations and variable slowly relative to the period of said interruptions.

5. Automatic electrical frequency control apparatus comprising an adjustable source of recurrent pulses of variable frequency oscillations separated by time intervals of duration different from the duration of said pulses, discriminator means coupled to said source to derive output potential pulses of polarity and magnitude respectively dependent on the direction and extent of variation of the frequency of said oscillations from a predetermined frequency, a detector coupled to said discriminator means to receive said output potential pulses and to produce a direct-current output signal dependent on the alternating components of said pulses, and means responsive to said direct-current output signal and operatively coupled to said source for adjusting the frequency of oscillation of said source in a direction to reduce said variation from said predetermined frequency.

6. Electrical apparatus comprising a source of oscillations periodically alternating between a first amplitude during intervals of a first time duration and a second amplitude during intervals of a second time duration longer than said first duration, rectifier means coupled to said source for producing a signal having alternating-current and direct-current components and characterized by periodic alternation between a first value of said signal during intervals of said first time duration and a second value thereof during intervals of said larger time duration, means for amplifying only said alternating-current components, and further rectifying means having an input circuit coupled to said amplifying means to receive said amplified alternating-current components and an output circuit including filter means, whereby an amplified version of said direct-current signal component is produced.

7. The method of producing an amplified version of the direct-current component of the envelope of an oscillatory wave characterized by cyclic variations from one value during repetitive time intervals to a second value during longer time intervals alternate with said first time intervals, comprising detecting said wave to produce its envelope, selecting and amplifying the alternating components of said envelope to produce a resultant signal, detecting said resultant signal to produce a signal having a direct-current component, and filtering said direct-current component.

8. Electrical frequency control apparatus comprising an intermittently operating adjustable source of electrical oscillations, means coupled to said source for adjusting the frequency of said oscillations in accordance with an electric signal potential applied thereto, frequency sensitive means having an input circuit for receiving a version of said oscillations and also having an output circuit coupled to said frequency adjusting means for applying thereto a signal potential varying according to variation of the frequency of said oscillations from a desired frequency, whereby said source is adjusted to suppress said variation from said desired frequency, means for coupling said source to said input circuit, and means operative in synchronism with the inter-

mittent operation of said source for rendering said coupling means inoperative during intervals between transmission periods whereby said frequency sensitive means is rendered incapable of receiving extraneous signals during said intervals.

9. Electrical frequency control apparatus comprising an intermittently operating source of ultra-high frequency oscillations, an ultra-high frequency oscillator having a voltage-sensitive frequency controlling element, a mixer coupled to said source and said oscillator for deriving a heterodyne signal of frequency equal to the difference of frequencies of said source and said oscillator and frequency responsive means having an input circuit coupled to said mixer to receive said heterodyne signal and also having an output circuit coupled to said element to vary the frequency of said oscillator in a manner to suppress variations of said heterodyne signal frequency from a desired frequency, and means for blocking said input circuit to the passage of high frequency waves and in synchronism with the intermittent operation of said source, whereby said circuit is in conductive condition only during periods of operation of said source.

10. Electrical apparatus comprising a source of oscillatory energy having an element responsive to an electrical potential to control the frequency of said source over a predetermined range, frequency-responsive means coupled to said source to receive oscillatory energy therefrom and adapted to produce a substantially direct potential having magnitude varying in accordance with deviations of source frequency from a desired frequency, control means having a pair of input terminals and interconnecting said frequency responsive means and said element for varying the potential of said element in response to said direct potential to vary said source frequency in a sense to reduce said direct potential, a condenser connected across said input terminals, manually operable means for short-circuiting said input terminals to apply an extreme potential to said element whereby said source frequency is adjusted to an extreme value and for simultaneously charging said condenser to a predetermined potential, and means operable upon release of said manually operable means for slowly discharging said condenser and for applying the decaying voltage of said condenser across said input terminals to slowly vary said element potential toward an opposite extreme, whereby in the absence of direct potential output from said frequency-responsive means said source frequency is varied from said extreme value toward the opposite extreme, and upon approach of said source frequency near said desired frequency, said direct potential maintains said element potential at a value producing substantially said desired frequency.

11. In a high frequency apparatus having means for transmitting high intensity high frequency electromagnetic energy and means for re-

ceiving relatively low-intensity electromagnetic energy reflected from a distant object, the combination comprising a high frequency oscillator having a frequency-controlling element, a first mixer responsive to low-intensity signals and subject to saturation in response to high-intensity signals coupled to said receiving means and said oscillator for deriving a heterodyne signal for producing indications of said object, a second mixer coupled to said oscillator, attenuating means coupling said second mixer and said transmitting means for applying an attenuated portion of said high-intensity energy to said second mixer whereby said second mixer produces a frequency-controlling heterodyne signal whose frequency is dependent upon the frequencies of said high-intensity high-frequency energy and said oscillator, and means responsive to said frequency-controlling signal and connected to said frequency-controlling element to vary the frequency of said oscillator in accordance with said frequency-controlling signal to suppress variations of the latter from a desired frequency.

12. High frequency apparatus comprising a transmitting channel for high-intensity electromagnetic energy, a receiving channel for receiving relatively low-intensity electromagnetic energy reflected from a distant object, a high frequency oscillator having a frequency-controlling element, a first mixer responsive to low-intensity signals and subject to saturation in response to high-intensity signals coupled to said receiving channel and said oscillator for deriving a first beat signal of frequency equal to the difference between the frequencies of the received energy and said oscillator, utilization apparatus connected in said receiving channel for transforming said beat signal into indications of said object, a second mixer loosely coupled to said transmitting channel and said oscillator whereby said mixer produces a second beat signal whose frequency is dependent upon the frequencies of said high-intensity high-frequency energy and said oscillator, and frequency-responsive means connected to said second mixer and having an output circuit coupled to said frequency-controlling element to vary the frequency of said oscillator in accordance with said second beat signal to suppress variations of said second beat signal frequency from a desired frequency.
